UNITED STATES PATENT OFFICE.

FLORENCE C. BIGGERT, JR., OF PITTSBURGH, PENNSYLVANIA, ASSIGNOR TO UNITED ENGINEERING AND FOUNDRY COMPANY, OF PITTSBURGH, PENNSYLVANIA, A CORPORATION OF PENNSYLVANIA.

ROLL-ADJUSTING MECHANISM FOR ROLLING MILLS.

Application filed October 22, 1925. Serial No. 64,103.

To all whom it may concern:

Be it known that I, FLORENCE C. BIGGERT, Jr., a citizen of the United States, residing at Pittsburgh, in the county of Allegheny and State of Pennsylvania, have invented 5 a new and useful Improvement in Roll-Adjusting Mechanism for Rolling Mills, of which the following is a full, complete, and exact description.

10 This invention relates to rolling mills, and more particularly to a roll adjusting mechanism therefor.

In the usual rolling mill the rolls are supported at opposite ends in roll housings, 15 and a screw is usually provided in each housing by means of which one of the rolls may be adjusted up and down to vary the pass between the rolls. Adjustment of the rolls must be made with great accuracy and precision, and at the same time the adjustment 20 must be made with considerable rapidity.

It has been proposed to connect the screws at each side of the housing by a common operating shaft so as to raise or lower opposite 25 ends of the same roll in unison. Such an arrangement, however, is not sufficiently flexible to permit of the rapid adjustment of one end of the roll with respect to the other for the correction of wear or for any other 30 purpose where it may be necessary or desirable to effect a movement of one roll with respect to the other to vary or establish the desired angular relationship of the roll axes.

35 According to the present invention it is proposed to provide a common operating means for raising or lowering both ends of the rolls in unison, but wherein a differential gearing is provided of such construction 40 as to be effective on the adjusting mechanisms for opposite ends of the rolls to enable such relative movement as may be necessary to be obtained quickly and accurately. The arrangement, furthermore, is one that lends 45 itself readily to an installation where the control for the differential is remotely located with respect to the differential or to the rolls. In other words, such relative adjustment may be obtained without the necessity of the roll operator actually mounting 50 the mill to make the adjustment.

The nature and advantages of the inven-

tion may be readily understood by reference to the accompanying drawings, wherein one embodiment of the invention is illustrated. 55 In the drawings, Figure 1 represents, more or less diagrammatically, a rolling mill having my invention applied thereto.

Figure 2 is a plan view of a mill embodying the invention. 60

Figure 3 is a side elevation of the upper part of a mill equipped with my invention.

Figure 4 is an enlarged detail sectional view longitudinally through the differential.

Figure 5 is a transverse section in the 65 plane of line V—V of Figure 4.

Figure 6 is a diagrammatic view of a slightly modified arrangement.

By reference to Figure 1, the general scheme of the present invention may be understood. In this figure, which is generally schematic, A designates a rolling mill having an upper roll 2 carried in vertically movable bearing blocks 3 at each end thereof. The bearing blocks 3 are carried on adjusting screws 4 at each side of the machine. The screws 4 may be raised and lowered by operation of gear wheels 5 splined or otherwise slidably and non-rotatably connected with the upper ends of the respective 75 screws. The gears 5 are supported against vertical movement, but may be rotated to raise and lower the respective screws by gearing engaging the teeth on the periphery of these wheels. Fixed nuts 5* cause the 80 screws to raise or lower when said screws are rotated through the rotation of wheels 5.

I have shown the wheels or nuts as being provided with worm teeth. One of these wheels engages a worm 6 on a shaft 7, while 90 the other wheel 5 engages a worm 8 on a shaft 9. Worms 6 and 8 are reversed with respect to each other. Interposed between shafts 7 and 9 is the differential gear, designated generally as 10.

Shaft 9 is connected with a main driving motor 11 through reduction gearing at 12. Motor 11 is of the reversible type.

On the opposed ends of shafts 7 and 9 within the differential are opposed bevel 100 gears 13. These are connected through pins 14 on a revolving ring or frame 15. Around the frame 15 is a worm wheel 16 meshing with a driving worm 17 on a shaft

18. Shaft 18 is connected to a reversible driving motor 19 through gearing 20.

In operation, motor 11 operates shaft 9 to turn the wheel or nut 5 at one end of the roll housing and to also rotate shaft section 7 in the reverse direction, the revolving ring 15 being held against rotation by worm 17. Inasmuch as worm 6 is reversed with respect to worm 8, the wheel 5 on the screw 10 at the other end of the housing is turned in the same direction at the same speed as that nut which is driven directly by the worm 8 on shaft 9.

When it is desirable to raise or lower one end of the roll faster than the other to make a necessary adjustment, motor 19 is operated to turn frame 15 through worm 17 in a direction to accelerate or retard the speed of rotation of shaft 7 with respect 20 to shaft 9.

In the arrangement shown in Figure 6, 25 designates roll adjusting screws, and 26 is the main operating shaft having a driving pinion 27 at one end thereof. On one 25 of the screws 25 is a worm wheel 28 engaging a worm 29 on the shaft 26. On the end of shaft 26 opposite pinion 27, is the differential gear 30 which drives worm 31 rotatable on shaft 26. Worm 31 meshes 30 with a worm wheel 32 on the other screw 25. This modification merely illustrates the adaptability of the invention to different locations, according to the particular requirements of individual installations.

35 The advantages of the present invention arise from the provision of means by which opposite ends of the adjustable rolls may be moved simultaneously at the same or at relatively different speeds, and whereby opposite ends of the rolls may be adjusted 40 relatively to each other to any degree within desired limits. A further advantage of the invention resides in the provision of means which may be controlled at a remote 45 point.

It will be understood that throughout the specification and claims the expressions "between" or "operatively effective between" are used generically, and not as designating 50 the actual physical location of the differential with respect to other parts of the mechanism.

It will be apparent that various changes or modifications may be made in the construction 55 of the apparatus within the contemplation of the invention and under the scope of my broader claims.

I claim as my invention:

1. In a rolling mill having an adjustable 60 roll and an adjusting mechanism for each end of the adjustable roll, and means including a differential gearing for simultaneously adjusting opposite ends of the roll.

2. The combination with a rolling mill 65 having an adjustable roll therein and having

adjusting means for each end of the adjustable roll, of a common driving mechanism for each of the adjusting means, and motor actuated means for moving one of the adjusting means relatively to the other. 70

3. In a rolling mill having an adjusting screw at each side thereof for effecting an adjustment of one of the rolls, means for actuating the screws in unison, and a differential gear through which the actuating 75 means operates on at least one of the adjusting screws.

4. In a rolling mill having an adjusting screw at each side thereof for effecting an adjustment of the rolls, a common operating 80 mechanism for both screws, and a differential gearing operatively interposed between the operating mechanism and one of the screws.

5. In a rolling mill having an adjusting screw at each side thereof, a gear wheel for effecting the operation of each, a drive shaft geared to the gear wheel for one of the screws, a differential gearing operatively effective between the drive shaft and the 90 gear wheel for the other screw, and operating means for the differential gearing.

6. In a rolling mill having a roll adjusting screw at each side thereof, a gear wheel for effecting the operation of each screw, 95 a drive shaft geared to the gear wheel for one of the screws, a motor for operating said drive wheel, a differential operatively effective between the drive shaft and the gear wheel for the other screw, and a motor 100 operatively connected with the differential.

7. In a rolling mill having a roll adjusting screw at each side thereof, operating means for effecting the operation of each screw, a drive shaft for each operating means, a differential gearing operatively interposed between the two drive shafts, 105 means for driving one of the drive shafts, and means for driving the differential.

8. In a rolling mill having a roll adjusting screw at each side thereof, a pair of drive shafts through which motion is imparted to the respective screws, a differential gear operatively interposed between the two drive shafts, means for driving one of the 115 drive shafts, and operating means for the differential gear.

9. In a rolling mill having an adjusting screw at each side thereof, a pair of operating shafts geared to the respective screws, 120 means for rotating one of the shafts, said shafts having opposed pinions thereon, a revolute frame having pinions thereon engaging said first mentioned pinions, and a motor for revolving said frame. 125

10. In a rolling mill having a roll adjusting screw at each side thereof, a gear wheel on each screw for effecting the operation thereof, a drive shaft for operating the gear for one screw, a second drive shaft for op- 130

- erating the gear for the other screw, a differential gearing connecting the two drive shafts, a reversible motor for operating said differential gearing, and a driving motor connected with one of the said drive shafts.
11. The combination with a rolling mill having a roll adjusting screw at each side thereof, means for operating one of the screws including a shaft and gearing, means for operating the other screw including a reversely arranged shaft and gearing, a differential gearing through which said shafts are operated in reverse directions, means for driving the differential gearing whereby one of the shafts may be accelerated or retarded with respect to the other, and a driving motor connected with one of
- the shafts for driving both of the shafts through said differential gearing.
12. The combination with a rolling mill having an adjustable roll therein and having adjusting means for each end of the adjustable roll, of a common driving mechanism for each of the adjusting means, and remotely controllable means for moving one of the adjusting means relatively to the other.
13. In a rolling mill, a roll, and means including a differential gear for simultaneously or relatively adjusting opposite ends of the roll.

In testimony whereof I have hereunto set my hand.

FLORENCE C. BIGGERT, JR.
